INVENTOR

C. B. Horton

UNITED STATES PATENT OFFICE.

CHASE B. HORTON, OF ELMIRA, NEW YORK.

BUCKWHEAT-HULLER.

Specification of Letters Patent No. 33,040, dated August 13, 1861.

To all whom it may concern:

Be it known that I, C. B. HORTON, of Elmira, Chemung county, State of New York, have invented a new and useful Improvement in Machines for Hulling and Polishing Buckwheat for Market; and I do hereby declare the following to be a correct description thereof, reference being had to the accompanying drawings and to the letters of 10 reference marked thereon.

The same letter refers to the same part wherever it occurs.

Figure 1. is a perspective view of the machine. Fig. 2. is a top view. Fig. 3. is a vertical section. Fig. 4. is a front view of air valve. Fig. 5. is a section of same. Fig. 6. is a vertical section of corrugated concave. Fig. 7. is an inside front view of same. Fig. 8. is a vertical section of upper concave. Fig. 9. is an inside view of same. Fig. 10. is a back view of lower elastic concave. Fig. 11. is a front or inside view of same. Fig. 12. is a vertical section of same. Fig. 13. is a back view of lower concave. Fig. 14. is a front or inside view of same. Fig. 15. is a vertical section of same, and Fig. 16. is a perspective view, of cylinder, and cheeks, through which its extremities pass, in detail.

This application is a modification of an 30 application on which a patent issued to me on the 28th day of August 1860, for new improved mechanism for hulling, pearling and polishing rice. The accompanying drawing is in most respects similar to the 35 one presented with that application. The Figs. 6, 7, 13, 14, 15 and 16, being more particularly applicable to this case will be hereinafter particularly described; but the others having been fully described in the case alluded to will not require to be again described in this application.

The nature of my invention consists in the improved device hereinafter described, for hulling buckwheat, to prepare it for market.

Referring to the accompanying drawing, A, marks the frame of the machine; B, the cylinder; C, driving pulley on same shaft with cylinder B; D, another pulley on the opposite end of the shaft, to drive fan F, by 50 means of a band working over pulleys D,

and E; U, the upper flexible concave of flexible corrugated steel plate; W, lower concave of cast iron, with stone concave X fitted thereto. Both these concave pieces are concentric with the cylinder B.

55

To enable others to make and use my improved huller, I will proceed to describe more fully its construction and operation.

The cylinder is constructed of "flint and stone," and is revolved on its axis by means 60 of any suitable power applied to pulley C. The ends of this cylinder, (see Fig. 16,) extend a short distance through cheeks a which nearly touch the outer surface of the cylinder; these cheeks allow free rotation of the 65 cylinder, and at the same time prevent the escape and loss of grain.

There are two concave rubbers U, and X, that are hung or supported by bolts or arms sliding in slots or grooves, for the purpose of 70 rendering them self adjusting. The upper concave rubber is held in a position concentric with the cylinder B, by springs pressing against its back, and is adjusted by screws, or other suitable devices, such as are represented at k, k. It is made flexible, so as to be self adjusting to suit any inequalities in feeding in the grain to be hulled. The lower concave rubber X, is of stone fitted in an iron plate W, which is held in a position concentric with cylinder B, by means of an adjusting screw I.

75 The grain is fed into the opening or hopper b, and before passing between the rubbing surfaces, is lifted and revolved in the 85 direction of the "doubled arrow," by the revolving cylinder B, upon which it falls, and is then carried around and between its surface, and the surfaces of the upper and lower concaves—receiving in its passage, the pressure of the elastic surface of U, which bears the grain against the surface of the stone cylinder B, whose rough exterior abrades the surface of the grains of buckwheat in its passage around, and so tends to hull and polish 90 it for market. The grain is further acted upon by its passage between the stone concave X, and the surface of the revolving cylinder B, which subjects it to a still more severe polishing operation.

100

Having thus fully described my invention, what I claim and desire to secure by Letters patent W, as and for the purpose specified.

1. The construction and use of the stone corrugated facing constructed and arranged concave X, in combination with its iron back Patent of the United States, is—

2. The elastic and flexible concave U with as and for the purpose specified.

3. The combination of cylinder B, with the cheeks a, in the manner and for the purpose specified.

The above specification, signed and witnessed this tenth day of August, A. D. 1860.

C. B. HORTON.
